In Germany May 11, 1934

5 Claims. (Cl. 93—62)

The present invention relates to seal-flap gumming and drying in envelope machines. The invention resides in a novel and highly useful arrangement by which to prevent the seal-flap, which has gum applied to its edge coincidentally with the reception of the folded part of the envelope blank in a compartment of the drying chain, from sticking or adhering to the moving gumming device or instrumentality, and thereby upsetting said chain's seizure and handling of such folded envelope part. Other and further objects and advantages of the invention will appear from the following detailed description, taken in connection with the accompanying drawing, in which—

15 Fig. 1 is a view in side elevation of an envelope machine's seal-flap gumming and drying devices in accordance with my invention.

Fig. 2 is a plan view of the arrangement shown in Fig. 1.

20 Like reference characters refer to like parts in both figures.

The drawing illustrates certain instrumentalities which are provided near the delivery or finishing end of an envelope-folding machine,— which latter provides suitable mechanism, not shown, for folding in and sticking down the side flaps *a*, *a* and the bottom flap *b* of successive envelope blanks, and for forwarding such articles in succession, bottom folds foremost, to the herein- illustrated devices for applying glue or gum to each article's trailing extended closure or seal flap *c*, which preferably has previously been scored or bent on fold line *c'*. In the arrangement illustrated, each such article is presented flatwise to the bight or pinch of a driven lower roller *1* and a pair of spaced cooperating upper rollers *2*, *2*, the latter carried by suitable pivoted arms *3*, *3*, and resting by gravity on the lower roller *1*, so as to 30 engage and feed the envelopes by their side edges only. This spacing of the rollers *2*, *2* prevents them from interfering with the operation of the device, now to be described, for applying gum or glue to the free edge or extremity of the extended 35 seal flap *c* of each article fed between said rollers.

Above the rollers *1* and *2*, *2* is a shaft *4*, adapted to rotate in synchronism with the rotation of roller *1* and carrying a pair of segmental ribs *5*, *5* (only one being shown in Fig. 1), which are divergent 40 from each other in such manner that their edge surfaces, in the rotation of shaft *4*, will register substantially with the edge areas *6*, *6* of seal flap *c* as the latter travels over the roller *1*. In the rotation of shaft *4*, the edges of the ribs *5*, *5* receive glue from contact with a roller *7*, that in turn

contacts with a roller *8* partially immersed in a glue receptacle *9*. The glue so received is transferred to the edges of seal flap *c* while the latter is on the roller *1*, such roller *1* serving as a bed or platen to support the seal flap during this gluing 5 or gumming operation.

In the forward movement of each article or envelope that carries the seal flap *c* into glue-receiving position, the already-folded bottom part of the envelope is projected into one of the open compartments of an endless drying chain, here shown as passing around sprockets concentric with a roller *10* and having a counterclockwise rotation, Fig. 1, so that the chain in its travel provides empty compartments moving toward the gumming devices on the upper course of said chain, the same compartments having a receding travel on the lower course of said chain. As here shown, the compartments are constituted by a series of overlapping plates *11*, *11* suitably attached to and 10 normally lying substantially flat against the chain links *12*, *12*, as the latter travel through the horizontal upper and lower courses of chain movement. However, when the links *12*, *12* are rounding their sprockets, the plates *11*, *11*, as shown in 15 Fig. 1, are thrown into different angular positions relative to each other, and said links *12*, *12* thereby open up spaces between adjacent plates to provide a succession of compartments which are 20 presented in properly timed relation to the delivery of the folded articles or envelopes by the rollers *1* and *2*, *2*, so that an envelope enters each 25 open chain compartment at about the time its seal flap is having gum applied thereto by the ribs *5*, *5*. The compartments tend to remain open 30 while the chain is passing around the sprockets, and gradually close up, to grip and hold the envelopes received therein as the chain flattens out 35 on its lower course beyond the roller *10*.

With drying chains of this type heretofore used, 40 the tendency of the envelopes received in successive compartments rounding the end roller of the chain to drop out by gravity before the plates *11*, *11* have a chance to close and grip the work, has been counteracted by the use of suitable 45 guides or supports arranged to be engaged by the open seal flap portions *c*, *c*. But such guides have proved generally unsatisfactory, because in the traverse of the same by successive freshly-gummed seal flaps, the latter are apt to contact 50 with each other and thereby cause adjacent envelopes to stick together. And still another difficulty in seal-flap gumming and drying arrangements of the chain type herein illustrated is the 55 tendency for each seal flap to adhere to and

therefore to be shifted by the moving gum or glue-applying devices, such as shown herein at 5, 5,—this, of course, upsetting the correct positioning of that part of the envelope which has 5 already entered an open compartment of the drying chain. Both of these difficulties are overcome and eliminated by my invention in the following manner:—

As shown in the drawing, that part of the bed or platen roller 1 which, in the rotation of said roller, always engages with and underlies the seal flap c of each envelope, is provided with a suitable aperture or apertures 13, 13, the latter being in communication through the hollow interior of the roller with a hollow member 14 that is periodically connected with and disconnected from any suitable source of pressure or vacuum, not shown. During the engagement with each seal flap of the glue-applying members 5, 5, the suction is effective through the apertures 13, 13 to hold said seal flap fast to the roller 1, and thereby to overcome any tendency of the same to stick to and move with the glue-applying devices 5, 5. In this way, the engagement of the gumming devices 5, 5 with the seal flap is not permitted to affect or upset in any way the proper reception of the envelope's other end in the open space 15 afforded by the separation of two of the plates 11, 11 as they start to round the roller 10. The release of the suction grip of roller 1 on each seal flap is appropriately arranged to occur, in the rotation of roller 1, at about the time that suction openings 16, 16 on the periphery of roller 10 become effective to grip and hold the other end of the envelope that has entered an open compartment of the drying chain. To this end, a hollow member 17, having connection with any suitable source of suction or vacuum, not shown, is arranged to be connected through the interior of roller 10 with successive openings 16, 16 of said roller as such openings, in the counterclockwise rotation of said roller, arrive opposite to and thereafter move along an elongated segmental port 18, Fig. 1.

In this way, each envelope or article, as its advancing folded end is received in an open compartment of the chain, is seized or gripped at such end by suction exerted through such of the openings 16, 16 as at that time are just coming 50 into registry with the port 18; this suction is maintained through the openings 16, 16 in question during the traverse of such openings along the arc of the port 18, or until the suction-seized envelope has been carried down around the roller 10 to substantially the point where the chain 12 passes off on its lower course, tangentially to the periphery of said roller. At this point, the suction is broken or released, but at this point the successive plates 11, 11 of the chain assume substantially horizontal positions, closing in on each interposed folded envelope portion to grip and hold the same in substantially horizontal position all through its travel along the lower course of the drying chain. Each envelope so gripped and moved by the chain has its freshly-glued seal flap c extending downwardly, substantially at right angles to its folded body portion, and as a consequence, not only are the seal flaps c, c kept positively out of contact with each other, but also 65 there is maximum exposure of the wet gum on

said seal flaps to the air, for the rapid and complete drying of said gum. It is to be particularly noted that provision for suction-gripping of the envelopes in the successive compartments of the drying chain is effective throughout that portion of the movement of each compartment when same is in open or non-gripping relation to the envelope received therein. In the absence of such suction gripping, the envelopes would be free during such movement to drop out of the compartments, and this would necessitate the use of guiding and supporting devices over which the seal flaps c, c would be dragged,—an operation which necessarily involves contact of adjacent seal flaps with each other and the danger of transferring or smearing the freshly-applied glue thereon. This difficulty is entirely eliminated by the present invention, which does away with any devices in contact with the seal flaps after the wet gum has been applied thereto.

I claim:

1. In seal-flap gumming and drying mechanism for envelope machines, a moving gumming device, a cooperating bed roller, and suction means provided by said roller and operable on each seal flap to prevent same from sticking to and from being moved by the gumming device.

2. In seal-flap gumming and drying mechanism for envelope machines, a moving gumming device, a cooperating bed roller, a drying chain 30 onto which each envelope is fed by said device and roller, and suction means provided by said roller and operable on the seal flap of each envelope to prevent the gumming device, by adhesion of said flap thereto, from displacing the 35 envelope from the position initially assumed by it on said drying chain.

3. In an envelope machine, a gumming mechanism for the seal flaps of successively-presented envelopes, and a drying chain receiving said envelopes from said gumming mechanism, in combination with suction means associated with the gumming mechanism and operable on each seal flap, for maintaining the delivery position of each envelope on the drying chain.

4. In an envelope machine, a gumming mechanism for the seal flaps of successively-presented envelopes, and a drying chain receiving said envelopes from said gumming mechanism, in combination with suction means associated with the 50 gumming mechanism and operable on each seal flap, for maintaining the delivery position of each envelope on the drying chain, and suction means associated with said drying chain, and brought into action substantially coincident with the release of the seal flap by the first suction means, for maintaining such delivery position while the chain travel is being reversed.

5. In an envelope machine, an endless drying chain providing a succession of compartments, 60 the latter being constituted by plates attached to the chain and normally lying in shingled relation while travelling along the flat upper and lower chain courses, said plates spreading apart for the introduction of envelopes between them, in the 65 zone of chain movement between said courses, and suction means operable in such zone for supporting the envelopes until said plates close in on one another and resume their shingled relation.

MAX GODER. 70
